CLAIM

The ornamental design for an admixing apparatus for fertilizer, as shown or described.

DESCRIPTION

FIG. 1 is a perspective view of an admixing apparatus for fertilizer showing our new design;

FIG. 2 is a front elevation thereof;

FIG. 3 is a top plan view thereof;

FIG. 4 is a bottom plan view thereof;

FIG. 5 is a side elevation thereof, the opposite side being identical in appearance; and

FIG. 6 is a rear elevation thereof.

FIG. 1

FIG. 2

FIG. 3

FIG. 4

FIG. 5

FIG. 6
